Harold A. Reuter, Cleveland, Ohio, assignor to Visioneering Company, Inc., Cleveland, Ohio, a corporation of Ohio

Application June 17, 1952, Serial No. 294,096

6 Claims. (Cl. 103—4)

This invention relates to an improved hydraulic apparatus which can be used either as an hydraulic pump or an hydraulic motor.

Heretofore, a number of machines have been proposed which may function either as an hydraulic motor or an hydraulic pump, and which are completely reversible in their operation. The amount of power such machines can handle depends upon size, and also, in large part, on the amount of fluid pressure which can be tolerated without incurring excessive losses due to leakage. Frictional losses of moving parts and internal frictional losses due to the viscosity of the fluid combine to further limit the amount of power which can be handled by the hydraulic unit. While units have been built which are capable of delivering high torque by virtue of the effective working pressure of the fluid system, prior art designs have been complicated and expensive to construct, and have not been readily adapted to be assembled or compounded as a plurality of units connected end to end and used alternatively or collectively.

It is the general object of this invention to avoid and overcome certain of the foregoing limitations in the prior art practices by the provision of an hydraulic pump-motor which is compact, efficient, simplified in its construction and assembly, and foolproof in operation.

Another object of the invention is to provide an hydraulic motor-pump in which leakage is held to a minimum even with very light grade oils, resulting in reduction of losses due to moving parts, area of sliding surfaces, viscosity of the working fluid, and leakage of fluid from the system.

Another object of the invention is the provision of an hydraulic machine in which individual units can be readily stacked or compounded in sections coupled to a common drive shaft.

Another object of the invention is to provide a motor-pump which is completely reversible in its operation.

Another object of the invention is the provision of a selectively compounded motor-pump in which units or sections can be cut into or by-passed from the hydraulic system whereby the speed, torque, and volume of fluid of the motor-pump can be readily controlled.

These and other objects of the invention which will become apparent as the description proceeds are achieved by the provision of a rotary hydraulic machine comprising a pair of cylindrical plates secured in adjacent relationship, the plates having a cylindrical bore and a pair of spaced holes passing therethrough, the holes being counterbored in one of the plates and being of such diameter as to intersect the cylindrical bore. A rotor is rotatably secured within the bore and has a pair of flanges intermediate the end of the rotor which slidably engage the wall of the bore, thereby forming an annular chamber between the flanges. A pair of vanes are secured to the rotor which bridge the annular space and are diametrically positioned, the vanes slidably engaging the wall of the cylinder bore. Rotary valve members are journaled in each of the spaced holes through the plates. An integral cylinder is formed

on each of the rotary valve members, the cylinder having a diameter and width substantially the same as the counterbores and rotating between the flanges of the rotor. Each rotary valve has a square broached hole in one of the journals which engages a shaft of square cross-section that also carries a spur gear having a similar square hole through its center. A shaft-supporting cover assembly is provided in sealed relation to one of the cylindrical plates, and a drive shaft, coupled to the main rotor, passes through the shaft supporting cover assembly and is journaled therein. A spur gear is rotatably secured to the drive shaft and meshes with the spur gears coupled to the rotary valve members, whereby the rotor and valves turn together. The cylinder portion of each valve is in rolling engagement with the rotor between the flanges, and each cylinder is provided with diametrically opposed notched-out portions for receiving the vanes as they pass the point of rolling contact between the rotor and valve cylinders. One of the cylindrical plates has a pair of fluid passages therethrough communicating with the annular chamber adjacent the rotary valve disc, and a cover plate is provided in sealed relation to one of the cylindrical plates opposite the shaft supporting cover assembly. The cover plate, cylindrical plates, and shaft supporting cover assembly are bolted together in a unit.

For a better understanding of the invention, reference should be had to the accompanying drawings, wherein:

Fig. 1 is an elevational view of the drive shaft end of the motor-pump;

Fig. 2 is a cross-sectional view of the invention taken substantially on the lines II—II of Fig. 1;

Fig. 3 is a cross-sectional view taken substantially on the line III—III of Fig. 2;

Fig. 4 is an enlarged, fragmentary, cross-sectional view of the inlet-outlet passage to which the fluid line is coupled;

Fig. 5 is a diagrammatic view of the valving and fluid system associated with the motor-pump; and

Fig. 6 is a fragmentary cross-sectional view taken substantially on the lines VI—VI of Fig. 3.

With specific reference to the form of the invention illustrated in the drawings, the numeral 10 indicates generally the motor-pump housing which is built up of one or more sections, each section including two cylindrical plates 14 and 16. While the invention contemplates that any number of sections 12 can be linked together in the method hereinafter described, the invention is illustrated as including two sections. Each section operates in the same manner as the other sections, and therefore, for the sake of clarity, the first section only will be hereinafter described in detail.

The plate 14 is provided with a cylindrical passage 18 therethrough and two smaller diameter holes 20. Pressed into the holes 20 are bearings 24, which may be of any type, preferably a sleeve type bearing. The holes 20 are counterbored to a larger diameter, as indicated at 28. It will be noted that the diameters of the counterbores are such as to intersect the cylindrical passage 18.

In a similar manner, the cylindrical plate 16 is provided with a cylindrical passage 32 and spaced holes 34. When the two plates 14 and 16 are assembled to form one section, the cylindrical passages 18 and 32, as well as the holes 20 and 34, are in axial alignment. Cylindrical passages 18 and 32, being substantially the same diameter, form a single cylindrical bore, indicated generally at 44, through the pump motor section 12. Sleeve bearings 38 are pressed into the spaced holes 34. The two plates 14 and 16 are bolted together by a plurality of bolts 40, and dowel pins 42 are employed to provide exact alignment between the plates.

Rotatably secured within the cylindrical bore 44 by means of bearings 46 and 48 is the rotor 50. The bearings

may be of any type such as ball, roller, sleeve, etc., depending on the load requirements. In the form of the invention illustrated, needle bearings are employed. The center of the rotor 50 is hollow and terminates in a shoulder 52 adjacent one end having a splined hole 54 therethrough. Two flanges 56 and 58, intermediate the ends of the rotor, are integrally formed on the outer periphery thereof and closely but slidably engage the inner walls of the bore 44, and are so spaced as to form an annular groove of substantially the same width as the depth of the counterbores 28. The flanges 56 and 58 combine with the bore 44 to form an annular chamber 60; a clearance of only .0005" being provided between the bore and the flanges to provide an effective seal against the seepage of oil under pressure from within the annular space past the flanges.

The rotor 50 is provided with a pair of vanes against which the hydraulic fluid can react as the fluid passes through the annular chamber 60. These vanes, which are located 180° apart, may be made integral with the rotor, but in the form of the invention shown, vane inserts 62 and 64 are employed which are received in slots 66 and 68 respectively cut into the rotor 50 in such a manner that the vanes bridge the annular chamber 60. The vanes slidably engage the bore wall with a sliding clearance of preferably about .0005" to hold leakage past the vanes to a minimum.

Operating in conjunction with the rotor 50 to effect proper flow of fluid through the annular chamber 60 into operative engagement with the vanes 62 and 64 are a pair of rotary valve members, indicated generally at 67. The rotary valve members include a disc-like valve cylinder or body 69 formed with trunnions 70 which are journaled in the sleeve bearings 24 and 38. The valve body 69 is substantially in the shape of a cylinder which rotates snugly in the counterbore 30. The outer circumference of the valve body is substantially identical with that of the inner circumference of the annular chamber 60 on the rotor. The width of the valve body 69 is such that it has a running fit between the flanges 56 and 58. Thus, the rotary valve members have rolling contact with the rotor 50. In order that the vanes of the rotors can turn past the valve bodies 69, a pair of notches 71, spaced 180° apart on each of the valve bodies 69, are provided. These notches alternately receive the vanes 62 and 64 as the rotor and rotary valve members revolve relative to each other.

To provide positive drive between the rotary valve members 67 and the rotor 50, spur gears are provided which mesh with each other and are coupled to the rotor and rotary valve members. Spur gear 72 has an internal spline 74 which engages with the spline shaft 76; the shaft 76 also engages with the splined hole 54 of the rotor 50. Spur gears 78 are coupled to the rotary valve members 67 by means of a shaft 80 which is preferably square in cross-section and passes through the square holes 82 broached in the end of the rotary valve members 67 and through similar holes 84 in the spur gears 78. Gear 72 and gears 78 have the same pitch diameter, which pitch diameter is equal to the diameter of the valve body 69, to insure rolling contact between the valve bodies 68 and rotor 50.

Closing one end of the motor-pump section 12 is a shaft supporting cover assembly 86 having an outer circular flanged cover portion 88 which abuts against the shoulder 90 of the cylindrical plate 14 when in assembled position. An O-ring 92 insures a pressure seal between the cover 86 and the plate 14. A bearing support bracket 93, welded or otherwise secured to the cover, has a ball bearing 94 pressed therein and secured in place by means of an internal snap-ring 96. The main shaft 76 is journaled in the ball bearing 94, as shown in Fig. 2. A rotary pressure seal 97 is provided to seal the shaft 76 where it passes out of the pump housing to insure against leakage of fluid.

Fluid connection to the hydraulic motor-pump is provided through the pipe-threaded outlet-inlet passages 98 and 100, as shown in detail in Fig. 4, which communicate with the annular chambers 60 adjacent the rotary valve bodies 69 and can be drilled or broached as shown. See Fig. 3. While the inlet-outlet passages are illustrated with pipe thread connections, it is to be understood that any type of fluid couplings can be employed to couple the motor-pumps to an hydraulic pressure line.

The invention as illustrated shows a second pump section 101 coupled to the first pump section 12 above described. The second pump section is identical in construction with the first with the exception that the unit illustrated employs a rotor having a wider annular chamber. It will be understood that the width of the annular chamber can be varied over any desirable range within reason, depending on the amount of power which is to be transformed by the motor-pump unit. Of course, the valve body portion of the rotary valve members has to be made correspondingly wide to snugly fit within the flanges on the rotor. The rotor and valve members of the additional motor pump units are coupled to the main shaft 76 and the square valve shafts 80 to effect proper rotation and to couple the sections together to provide unitary operation.

A cover 102 seals off the end of the motor-pump opposite that of the bracket-cover assembly 86. The cover 102 is secured in sealed engagement with the pump section by means of an O-ring 104. It is to be understood that if only one pump section is used, the cover 102 is secured directly to the cylindrical plate 16, the shaft 76 and the shaft 80 being terminated flush with the outer face of the spur gears 72 and 78. Covers 86 and 102 are secured in place by four bolts 106, which pass through the pump sections and secure the covers and various plates making up the pump-motor section into an assembled unit. Base members 108 are secured by means of bolts 110 to provide mounting means for the motor-pump.

In operation, the motor-pump described can function either as a hydraulic pump or a hydraulic motor and is completely reversible. When serving as a pump, for example, the shaft 76 is rotated by an external means (not shown), driving the rotor in the direction indicated by the arrow. See Fig. 3. As the rotor revolves, hydraulic fluid, trapped to the left of the vane 64 when in the position illustrated in Fig. 3, is forced ahead of the vane through the outlet passage 100. While the vane 62 passes the notch 71 in the valve body, fluid can by-pass the vane 62 because the vanes do not come in contact with rotary valve bodies. However, during the time the vane 62 is passing the first valve body, in the position illustrated in Fig. 3, the fluid forced ahead by the vane 64 is stopped by the second valve body, which is then in rolling contact with the rotor. Thus it is seen that during the time the vane 62 passes the first valve, fluid forced ahead by the vane 64 reacts against the barrier imposed by the rolling contact of the second valve and the rotor, and therefore in turn is forced under pressure out through the outlet passage 100. At the same time, movement of the vane 64 creates a partial vacuum on the back side which draws oil into the inlet passage 98. As the rotor continues to rotate, the vane 62 comes around in position where it passes the inlet opening 98 and traps oil ahead of it which in turn is forced out of the outlet passage 100 in a manner similarly described in connection with the vane 64. Where the motor-pump is utilized as a motor only, the operation is identical with the exception that fluid under pressure reacts against the vanes rather than the vanes reacting against the fluid as in the above-described operation.

Fig. 5 illustrates the fluid piping system when more than one section is employed. For example, with two sections, both sections may be used as either pumps or motors in parallel by opening valves 112, 116, 118, and 122 and closing valves 114 and 120. As indicated by the dash line,

valves 112, 114, and 116 may be mechanically coupled so that when valves 112 and 116 are closed, for example, valve 114 is open, or if valves 112 and 116 are open, valve 114 is closed. Likewise with valve 118, 120, and 122, or valves associated with any additional sections that may be employed. It is evident that with valves 112 and 116, in section 12, for example, being open and valve 114 closed, fluid passes through that particular section. By closing valve 112 and 116 and opening valve 114, flow through section 12 is cut off, although fluid already trapped within the section can freely recirculate through the by-pass of valve 114.

While, in accordance with the patent statutes, certain best known embodiments of the invention have been illustrated and described, it is to be particularly understood that the invention is not limited thereto or thereby, but that its scope is defined in the appended claims.

I claim:

1. An hydraulic motor or pump including a plurality of cylindrical motor or pump sections, each section including a vaned rotor and pair of associated rotary valve members, a circular lip projecting beyond one face of each section and engaging a shoulder around the edge of the opposite face of an adjoining section, a circular cover having a shoulder around the edge engaging the projecting lip of one end section, a circular shaft-end cover having a circular lip engaging the shoulder around the edge of the other end section, bolt means securing the covers and sections together in fluid-tight relationship with an enclosed fluid-tight space provided between adjacent sections, a drive shaft passing through and coupled to the rotor in each section, said shaft extending through the shaft-end cover, a rotary seal secured to the shaft-end cover and adapted to seal the shaft opening against leakage of fluid, each of said sections having a pair of fluid inlet or outlet passages communicating with the rotor, a valve associated with each inlet or outlet passage, a fluid by-pass line directly interconnecting the inlet or outlet passages of each section intermediate the valve and the rotor, and a valve in each of said fluid by-pass lines, the by-pass valve and inlet or outlet valves of each section being mechanically coupled whereby the by-pass valve opens when the inlet or outlet valves are closed to permit recirculation of fluid through the section when it is cut off from the fluid source.

2. An hydraulic motor or pump including a plurality of cylindrical motor or pump sections, each section including a vaned rotor and pair of associated rotary valve members, bolt means for securing said sections together in fluid-tight relationship, shaft means for coupling the rotary valve members in adjacent sections, cover means in sealed relationship with the end sections whereby the covers and sections form a fluid-tight unit, a drive shaft passing through and coupled to the rotor in each section, said shaft extending through said cover means, a rotary seal between the shaft and cover means and adapted to seal the shaft opening against leakage of fluid, each of said sections having a pair of fluid inlet or outlet passages communicating with the rotor, a valve associated with each inlet or outlet passage, a fluid by-pass line interconnecting the inlet or outlet passages of each section intermediate the valve and the rotor, and a valve in each of said fluid by-pass lines, the by-pass valve and inlet or outlet valves of each section being mechanically coupled whereby the by-pass valve opens when the inlet or outlet valves are closed to permit recirculation of fluid through the section when it is cut off from the fluid source.

3. An hydraulic motor or pump including a plurality of cylindrical sections, each section having a circular lip projecting beyond one face of the section, a shoulder around the circumference adjacent the edge of the other face of the section, the lip of one section fitting against the shoulder of an adjoining section in sealed relationship, the lip providing a sealed space between the adjacent sections when in assembled position, a bore through each

section, said bores being in axial alignment, a plurality of rotors having a splined hole through the center, one rotor being journaled in each of the bores, a main drive shaft splined over a portion of its length and engaging with the splined hole in each of the rotors whereby the rotors and shaft rotate as a unit, a pair of rotary valve means operatively associated with each rotor, said rotary valve means having a square hole axially positioned therethrough, a square shaft passing through the rotary valve means in each section, a second square shaft passing through the other of said rotary valve means in each section, said square shafts rotatively coupling the valve means in each section, spur gears mounted for rotation on said square shafts between adjacent sections, spur gears meshing with said spur gears and mounted on the spline shaft whereby the rotors and rotary valve means rotate in positive drive relationship, a circular cover having a shoulder around the circumference thereof fitting against the shoulder of one end section, a bracket-cover having a projecting lip fitting against the shoulder of the other end section, bearing means supported by said bracket-cover, the main shaft being journaled therein, rotary seal means secured to the bracket-cover and adapted to seal the shaft against leakage of fluid from within the motor or pump, each of said sections having a pair of inlet or outlet passages communicating with rotors, and valve means for diverting fluid from or to any section and including means directly connecting the outlet to the inlet of the same section for circulation of fluid in a cut-off section.

4. An hydraulic motor or pump unit including a multi-section frame means having a cylindrical bore therethrough and having an inlet and an outlet, a rotor journaled in said bore, the rotor having an annular groove around the circumference thereof intermediate the ends of the rotor, said annular groove combining with the wall of the bore to form an annular working chamber, the frame means having at least two fluid inlet or outlet passages therethrough communicating with the annular working chamber, a pair of rotary valve members journaled in the frame means, the rotary valve members being in rolling contact with the periphery of the rotor and providing fixed barriers therein to the flow of fluid through the annular chamber, a pair of vanes in diametrically opposed position secured to the rotor and bridging the annular chamber, the outer edge of the vanes being in sliding contact with the wall of the bore, the valve members having notched portions adapted to receive the vanes as the vanes pass the point of contact between the rotor and valve members, the vanes providing compartments in the working chamber individually and alternately connecting to the inlet or outlet with rotation of the valve members, means rotatably connecting the rotor and valve members in positive drive relationship, and bearings for said rotor, said multi-section frame means being counterbored on a face thereof to provide a recess for receiving parts of said rotary valve members therein.

5. In compounded combination, a plurality of hydraulic motor or pump units, each unit comprising frame means having a cylindrical bore therethrough and having an inlet and an outlet, a rotor journaled in said bore, the rotor having an axially short annular groove around the circumference thereof intermediate the ends of the rotor, said annular groove combining with the wall of the bore to form an annular working chamber, the frame means having at least two fluid inlet or outlet passages therethrough communicating with the annular chamber, a pair of rotary valve members journaled in the frame means, the rotary valve members being in rolling contact with the periphery of the rotor and providing fixed barriers therein to the flow of fluid through the annular chamber, a pair of vanes in diametrically opposed position secured to the rotor and bridging the annular chamber, the outer edge of the vanes being in sliding contact with the wall of the bore, the valve members having notched portions adapted to receive the vanes as the vanes pass the point of contact

between the rotor and valve members, the vanes providing compartments in the working chamber individually and alternately connecting to the inlet or outlet with rotation of the valve members, and means rotatably connecting the rotor and valve members in positive drive relationship; wherein the units are placed in end-to-end-relation with adjacent end frame means removed whereby the cylindrical bores of the frame means of adjacent units are in alignment and are separated only by the means connecting the rotor and valve members in positive drive relationship, means for releasably securing the frame means of the plurality of units together, means releasably connecting the rotors of the units together, means releasably connecting the respective valve members of the units together, a manifold inlet for supplying fluid to each unit, a manifold outlet for receiving fluid from each unit, a by-pass for circulating fluid directly from the outlet to the inlet of each unit, and valve means associated with each unit for closing the by-pass and connecting the manifold inlet and outlet to the unit whereby any number of selected units are effectively operated.

6. In compounded combination, a plurality of hydraulic motor or pump units, each unit comprising frame means having a cylindrical bore therethrough and having an inlet and an outlet, a rotor journaled in said bore, the rotor having an axially short annular groove around the circumference thereof intermediate the ends of the rotor, said annular groove combining with the wall of the bore to form an annular working chamber, the frame means having at least two fluid inlet or outlet passages there- 25 through communicating with the annular chamber, a pair of rotary valve members journaled in the frame means, the rotary valve members being in rolling contact with the periphery of the rotor and providing fixed barriers therein to the flow of fluid through the annular chamber, 30

25
30
35

a pair of vanes in diametrically opposed position secured to the rotor and bridging the annular chamber, the outer edge of the vanes being in sliding contact with the wall of the bore, the valve members having notched portions adapted to receive the vanes as the vanes pass the point of contact between the rotor and valve members, the vanes providing compartments in the working chamber individually and alternately connecting to the inlet or outlet with rotation of the valve members, and means rotatably connecting the rotor and valve members in positive drive relationship; wherein the units are placed in end-to-end relation with adjacent end frame means removed whereby the cylindrical bores of the frame means of adjacent units are in alignment and are separated only by the means connecting the rotor and valve members in positive drive relationship, means for releasably securing the frame means of the plurality of units together, means releasably connecting the rotors of the units together, means releasably connecting the respective valve members of the units together, a manifold inlet for supplying fluid to each unit, and a manifold outlet for receiving fluid from each unit.
